CASING MACHINE

Anthony R. Silva, San Jose, Calif.

Application June 27, 1949, Serial No. 101,575

9 Claims. (Cl. 226—14)

1

The present invention relates to container handling apparatus of the character disclosed and claimed in my copending application Serial No. 37,291, filed July 6, 1948, for Casing Machine, and it relates more particularly to a casing machine of that character for placing either bottles or cans into a case in an efficient and simple manner adaptable to high speed bottling or canning operations.

It is a general object of the invention to provide an improved casing machine in which the case is held in predetermined relation to the array of containers to be placed therein for pickup by the containers.

Another object of the invention is to provide a casing machine of the above character in which the container feed incorporates stop means of a character which will not injure the labels of the containers.

A further object of the invention is to provide a casing machine of the above character in which the cans or containers are fed in upright position into an array corresponding to the number in a case, and are then carried into the case as an array of containers is moved away from the array forming position.

Other objects and advantages of the invention will be apparent from the following description of a preferred embodiment thereof, as illustrated in the accompanying drawings, in which:

Figure 1 is a plan view of the discharge end of a casing machine embodying the instant invention.

Figure 2 is a side elevational view of the discharge end of the machine shown in Figure 1.

Figure 3 is a perspective view of the casing unit of the machine showing the case in operative relation with respect to an array of containers in position for casing.

Figure 4 is a sectional view illustrating the case in position with respect to an array of cans to be placed therein.

Figure 5 is an operational view showing the operation of the containers or cans in picking up the case from its support means.

Figure 6 is a plan view of a modified form of case transfer structure utilizing a pivoted case supporting arm and restraining mechanism therefor.

Figure 7 is a side elevation of the mechanism shown in Figure 6 with parts being broken away, and in section to show the case supporting arm in unreleased position.

Figure 8 is a side elevation of the mechanism shown in Figure 6 with parts being broken away, and in section to show the case supporting arm in released position.

The machine includes a mesh belt conveyor 10 which is trained about a driving drum 11 suitably journaled upon the frame 12 and driven

2

from a motor 13. Above the conveyor 10 are a plurality of separating partitions 14 into which four rows of containers such as cans are fed through suitable can dividing mechanism of the character disclosed in said above referred to application. The casing mechanism comprises a pair of casing units or trays 21 and 22 of similar construction and spaced 180° apart with respect to their common support shaft 23.

The unit 21, for example, comprises a series of vertically arranged strips 24 (Figures 1 to 4) extending from a normally horizontally disposed end plate 25 to one of a pair of transverse center plates 26 secured to the shaft 23. The vertical plates 24 provide partitions which form four pockets to receive four rows of three bottles each. The bottom of these pockets are formed by the end plate 25 and by a series of parallel rods 27 welded to the respective plates 25 and 26. As seen most clearly in Figure 4, the axis of the shaft 23 is raised sufficiently with respect to the upper stretch of the conveyor 10 that when a unit or tray 21 or 22 is in horizontal position and adjacent the conveyor, it forms a smooth continuation of the upper stretch of the conveyor 10 and the transfer plate 28 adjacent thereto. Thus, when a casing unit is in its home or full cycle position, it is in proper position to receive four rows of three bottles each. In this position the weight of the unit is supported by a spring-urged latch or full cycle element 30 (Figure 3) having respective upper and lower latch jaws engaging above and below the adjacent vertical plate or partition 24. The lower latch jaw may be provided with a suitable cam surface (not shown) so that the latch element can yield as the casing unit moves into its home position. The latch element 30 is connected pivotally to a cam lever 31 pivoted on the frame of the machine. Spring 31a connected to the lever 31 urges the latch element 30 to active position and positions the cam end of lever 31 in operative relation to the control 34 to be moved thereby upon starting of a cycle of operation.

In this position of the parts a can stop is held in inactive position to allow the rows of bottles to be fed onto a casing unit under the urgency of the oncoming containers on the conveyor 10. This stop takes the form of a plurality of fingers 32 carried by a transverse shaft 33 suitably journaled on the frame 12 of the machine. There are five fingers 32 spaced to engage the lower rims of the cans on the conveyor 10 when in upright position with the intermediate fingers 32 engaging a pair of adjacent cans of the row which are engaged with the stop fingers, as seen in Figure 3. The shaft 33 at one end carries an upright arm 34 which is connected by a link 36 with the control lever 37 for the drive mechanism of the casing trays including the clutch 38 (Figure 2) which is driven from the drum 11 as described

in said above referred to application. As the lever 37 is rocked clockwise, as viewed in Figure 2, to engage the clutch 38, the arm 34 on the shaft 33 with the stop fingers 32 thereon are also rocked clockwise to move these stop fingers to active position and prevent discharge of cans from the conveyor until the next support tray arrives at home position.

From the above description it will be seen that after twelve cans or bottles have been fed onto the cooperating support tray and the control lever 37 is rocked clockwise, the trays are unlocked by withdrawal of the full-cycle latch 30, the clutch 38 is engaged, and the fingers 32 are moved to active position as shown in Figure 3, so that the trays 21 and 22 are free to rotate through 180°. During the movement the tray 22 (Figure 3) will be lifted and the tray 21 moved toward active position downwardly from the position shown in Figure 3.

To enable accurate alignment of a case with respect to the array of cans or bottles to be placed therein, a case support structure or frame is provided in connection with the active tray 21 or 22, and this structure takes the form of a three-walled case support or hopper 41, 42 and 43 suitably supported on the frame of the machine by U-shaped bracket 44 and angle brackets 45. A strap 47 is provided at either side to connect the U-shaped bracket 44 and the respective angle brackets 45. The side case supports 41 and 43 are similar and have their upper surfaces angled with respect to the horizontal with the corners cut away or bevelled for support of a case thereon. The transverse support wall 42 is similarly cut away or bevelled at its ends to provide clearance for the corners of a case 46 when placed thereover as shown in Figures 3 and 4.

The angle of the upper edges of the case support element or walls 41 and 43 places the left edge of a case, as shown in Figure 4, downwardly over the ends of the cooperating array of cans, while the right edge is spaced slightly thereabove so that cans can pass beneath the wall 42 and the case. The case support elements 41 to 43 are positioned with respect to the path of travel of the cooperating tray 21, for example, such that upon counterclockwise movement of the tray 21, as shown in Figure 4, for example, the array of cans will enter the case as seen in Figure 5, and lift the case from its supporting structure. As the trays 21 and 22 are revolved through 180° the case with the cans therein is discharged onto the discharge conveyor 48, as disclosed in said above referred to application.

In operation, therefore, when an array of twelve cans has been fed onto the active tray 21 or 22 and a case 46 placed over the support structure 41 to 43 therefor, the operator moves the handle 37 so that the trays 21 and 22 are rotated through 180°, the active tray 22 with the array of cans thereon moves the cans into the case and then serving to lift the case from its support structure and to deliver the case bottom down onto the conveyor 48 as indicated by the case shown falling free in Figure 2 at 46a.

In Figures 6, 7 and 8 there is illustrated a modified form of the invention in which the delivery of the case 46 with the cans 55 therein from the active tray 21 or 22 to the conveyor 48 is assisted by means of a case supporting arm or structure which becomes effective to aid in preventing undue acceleration of the case 46 in its descent onto the conveyor 48.

The case supporting and guiding arm 51, which

is journaled on the shaft 23 is provided at its lower end with a lateral extension 51a which projects across the edge of a case 46 on the case supporting walls 41 to 43 at the side thereof opposite the operator. Carried by the arm 51 and movable therewith is a latch disk 52 and a sprocket 53 around which a chain 54 carrying a weight 56 extends. The weight 56 urges the arm 51 counterclockwise, as viewed in Figure 7, and the arm 51 is restrained against such movement by the engagement of a latch 57 with the latch face of the disk 52. The latch bar 57 is slidably mounted on the frame 12 and is urged by a spring 58 to active position and has a slotted end 57a engaging a pin 59 carried by an upwardly extending arm 61 on the control rock shaft 33. The shaft and the slotted end 57a of the latch bar 57 has some lost motion with respect to the pin 59 to time the release of the arm 51 and thereby its engagement with the case 46 with reference to the upward travel of the active can bearing tray.

In order to temporarily engage or connect the arm 51 to the shaft 23 during its return travel so that it moves with the case being lifted from the hopper structure 41—43, the arm 51 carries a gravity pawl 62 pivoted thereon at 63 and adapted in the operative upper position of the arm 51 as shown in Figure 8 to engage a gear 53 fast on the shaft 23.

In operation, when the clutch drive for the shaft 23 is engaged, as previously described, this is accompanied by a rocking movement of the shaft 33, and due to the lost motion in the slotted portion 57a of the latch bar 57, the tray 22 shown in active position in Figure 7 moves upwardly to position the cans 55 within the case 46 before the latch bar 57 has moved sufficiently to release the arm 51. The arm 51 is preferably timed in its release so that it is moved counterclockwise from the position shown in Figure 7 to the position shown in Figure 8 immediately before the cans 55 on the tray 22 start to lift the case 46 from the support structure 41—43 so that the cans, the tray and the case 46, together with the arm 51, start travelling as a unit clockwise from the position shown in Figure 8 to insure a gentle delivery of the case onto the conveyor 48. During such operation, the operator will normally assist in such gentle depositing by use of his hand on the opposite end of the case 46 from that engaged by the arm 51. If desired, a pair of arms 51 may be provided for the respective ends of the cases.

While I have shown and described a preferred embodiment of the invention, it will be apparent that it is capable of variations and modifications within the scope of the claims appended hereto.

I claim:

1. In a casing machine, means including a conveyor for supplying a plurality of parallel files of containers at the discharge end of the conveyor, casing mechanism at said discharge end including a plurality of successively active container supports with an active container support in alignment with the discharge end of the conveyor, a case support positioned above the active container support for movement of the containers on the container support into engagement within a case on the case support, a case supporting arm movably mounted on the machine and normally positioned in an inactive lower position, said arm cooperating successively with said container supports, and means for moving said case supporting arm upon initiating movement of containers on a container support into a case on said case

support to engage the arm with the case and for thereafter causing movement of the containers, the case and the arm to the case discharge position substantially as a unit.

2. In a casing machine, casing mechanism including a movable container support movable through a path, a case support positioned above the container support along said path for movement of the containers on the container support into engagement within a case on the case support, a movable case supporting arm normally positioned in an inactive position, and means for moving said case supporting arm upon initiating movement of containers on the container support into a case on said case support to engage the arm with the case and for thereafter causing movement of the containers, the case and the arm to a case discharge position substantially as a unit.

3. In a casing machine, casing mechanism including a movable container support, a case support positioned above the container support for movement of the containers on the container support into engagement within a case in inverted position on the case support, a movable case supporting arm normally positioned in an inactive position, means operating said container support to move the containers thereon into said case and to lift the case from the case support, and means for moving said case supporting arm upon initiating movement of containers on the container support into a case on said case support to engage the arm with the case, whereby the containers, the case and the arm move to a case discharge position substantially as a unit.

4. In a casing machine, casing mechanism including a movable container support for supporting an array of containers in upright position for engagement within a case in inverted position, a movable case supporting arm normally positioned in an inactive position, means for operating said container support to lift the containers and the case thereon and to carry them to a discharge position, and means for moving said case supporting arm upon initiation of movement of said container support to engage the arm with the bottom of the inverted case, whereby the containers, the case and the arm move to said case discharge position substantially as a unit.

5. In a casing machine, casing mechanism including a rotary container support for engaging and supporting an array of containers in upright position for movement into a case in inverted position, a pivotally mounted case supporting arm normally positioned in an inactive position, means for operating from container support to lift the containers and the inverted case thereon, and means for moving said case supporting arm upon initiation of movement of said container support to engage the arm with the inverted case, whereby the containers, the case and the arm move to a case discharge position substantially as a unit.

6. In a casing machine, means including a conveyor for supplying a plurality of parallel files of containers at the discharge end of the conveyor, casing mechanism at said discharge end including a plurality of successively active container supports with an active container support in alignment with the discharge end of the conveyor, said active container support being adapted to receive an array of containers in upright position from said conveyor for insertion into a case in inverted position, a case supporting arm movably mounted on the machine and normally positioned in an inactive position, said arm cooperat-

ing successively with said container supports, and means brought into play upon initiation of movement of an active container support away from its aligned position for causing engagement of said case supporting arm with the bottom of said inverted case, whereby said container support, said containers, said case, and said arm move substantially as a unit to discharge position.

7. In a casing machine, means including a conveyor for supplying a plurality of parallel files of containers at the discharge end of the conveyor, casing mechanism at said discharge end including a plurality of successively active rotary container supports with an active container support in alignment with the discharge end of the conveyor, said casing mechanism being adapted to receive an array of containers in upright position from said conveyor for insertion into a case in inverted position, a case supporting arm pivotally mounted on the machine and normally positioned in an inactive position, said arm cooperating successively with said container supports, and means brought into play upon initiation of movement of a container support away from its active position for causing engagement of said case supporting arm with the bottom of said case, whereby said container support, said containers, said case, and said arm move substantially as a unit to discharge position.

8. In a casing machine, casing mechanism including a movable container support for supporting an array of containers in upright position for engagement within a case in inverted position, a movable case supporting arm for engagement with the bottom of a case and mounted for movement between an upper case engaging position and a lower case delivering position, means for moving said arm from said case delivering position to said case engaging position, means for moving said container support to lift the container and the case thereon and to carry them to a discharge position, and means operated by said moving means to effect movement of said supporting arm with said case support and a case thereon from said case engaging position to said case delivering position.

9. In a casing machine, casing mechanism including a rotary container support for engaging and supporting an array of containers in upright position for movement into a case in inverted position, a case supporting arm pivoted coaxially with said container support and mounted for movement between an upper case engaging position and lower case delivering position, means for moving said arm from said case delivering position to said case engaging position, means for moving said container support to lift the containers and the case thereon and to carry them to a discharge position, and means operated by said moving means to effect movement of said supporting arm with said case support and a case thereon from said case engaging position to said case delivering position.

ANTHONY R. SILVA.
